UNITED STATES PATENT OFFICE

JOHN W. McCALLUM AND ALEC S. MUSCOVITCH, OF WINNIPEG, MANITOBA, CANADA

SNOW PLOW

Application filed November 7, 1929, Serial No. 405,432, and in Canada July 29, 1929.

The invention relates to improvements in snow plows which can be effectively used on railroads or elsewhere for maintaining the track or road clear and an object of the invention is to provide a device having a main plow which will cover an area wide enough to maintain the road bed clear of snow and equipped so that it will effectively scoop up and elevate either light or heavy quantities of snow on the road bed and discharge that snow in any selected location and wherein the main plow is adjustable vertically as a unit, such permitting of the varying of the depth of cut of the plow without altering the angular position thereof.

A further object of the invention is to provide a main plow having an inclined chute over which the snow may be elevated and to provide the chute with gates which can be opened to expose an endless driven elevating conveyor, such latter provision permitting of the effective elevating of the snow when slushy or wet snow is encountered or heavy drifts are met.

A further object of the invention is to provide in conjunction with the main elevating conveyor, a derrick-crane like rear conveyor for receiving the snow elevated by the main conveyor and controlled so that the attendant can deposit the snow where desired, and to associate with the rear conveyor a hopper adapted to turn with the same and to receive the snow discharging from the main conveyor and direct it to the underlying lower end of the rear conveyor.

A further object is to construct all of the aforesaid parts so that they will handle gravel or other commodities which might be encountered on the road bed.

A further object of the invention is to provide a plow having side elevators either of which can be operated in conjunction with the main plow and which will act to clear the selected area at the side of the track of snow or other material, the said material being elevated and discharged to the derrick-crane like rear conveyor above mentioned.

A further object is to construct the side conveyors so that they can be raised vertically as desired to vary the depth of cut and with-

out altering the angular position of the conveyor and also to arrange the said side conveyors so that the front end or nose can be swung upwardly to clear permanent obstructions such as signalling and switching devices adjacent the track.

A still further object is to construct the entire machine so that there will be no possibility of the material being handled clogging and also so that the various conveyors utilized will be power driven by suitable motors provided and such also that the moving of the main and side conveyors to their various adjusted positions can be accomplished by a motor drive directly under the control of the attendant.

A further object of the invention is to construct the various conveyors utilized so that they can be mounted readily on a flat car of usual type for railroad work and such that by modifying the carriage, the device can be used on highways or roads to equal advantage.

With the above more important objects in view, the invention consists essentially in the arrangement and construction of parts hereinafter more particularly described reference being had to the accompanying drawings, in which:

Fig. 1 is a side view of the complete device. 80

Fig. 2 is a plan view thereof.

Fig. 3 is a vertical sectional view at 3-3' Figure 2.

Fig. 4 is an enlarged horizontal sectional view at 4-4' Figure 3. 85

Fig. 5 is a side view of the inner side of one of the side conveyors.

Fig. 6 is an enlarged detailed cross sectional view at 6-6' Figure 3. 90

Fig. 7 is a detailed view showing the drum winding crank and associated parts.

Fig. 8 is a vertical sectional view at 8-8' Figure 3 and looking rearwardly.

Fig. 9 is an enlarged detailed horizontal sectional view at 9-9' Figure 1. 95

Fig. 10 is a perspective view of a modified type of side conveyor which may be employed.

Fig. 11 is a vertical sectional view at 100

11—11' Figure 10 and showing the adjacent rack bar in vertical section.

In the drawings like characters of reference indicate corresponding parts in the several figures.

The device as herein shown is particularly adapted for railroad work and the various operating parts are mounted on the customary flat car as used by railroads, the car presenting the platform 1 carried by front and rear truck wheels 2 and 3 mounted on the axles 4 and 5, the truck wheels running on the usual railroad tracks 6.

Centrally somewhat towards the front end 15 of the platform, we locate a prime mover such as a gasoline engine 7 which drives the main driving shaft 8 through suitable change gears (not shown) contained in a gear box 9. The shaft 8 carries a chain wheel 8' which is connected by a chain 8" passing through the platform and operating around a further chain wheel 10' secured to the forward end of a short shaft 10 carried by a bearing 11 secured to the under side of the platform. The shaft 25 10 is connected through a universal joint 12' with a further shaft 12 leading rearwardly to the axle 5 and provided with a worm 13 engaging continuously with a worm wheel 13' secured to the axle, the arrangement being 30 such that the rear axle of the car is driven through the parts above mentioned directly by the engine 7.

The engine shaft 7' drives the armature (not shown) of an electric generator 14 35 mounted on the platform in advance of the engine and this generator is utilized to supply in any suitable manner an electrical current to the various motors which we utilize for purposes later explained.

The front end of the car carries the main centrally located plow indicated generally by the reference numeral 15 which plow is vertically adjustable in respect to the platform so that the front end thereof can be raised or lowered in respect to the tracks.

The plow comprises opposing vertical side boards 16 which flare forwardly and are provided on their inner sides with lengthwise extending angle bars 17 and 17' (see Figure 6) to which we permanently secure the edges of an elevating plate 18, the forward lower end of the plate being adapted to lift snow or other material from the ground, the lifted material being subsequently passed upwardly 55 over the upper face of the plate and discharged over the elevated upper rear end thereof. It will be observed that the front ends of the side boards are provided with downwardly extending extensions 16" which 60 have their rear edges vertical and terminating adjacent the forward end of the car and their lower edges horizontal or parallel to the ground.

Similar reinforcing angle bars 19 are 65 secured to the lower sides of the extensions and

these are connected by a nose bar 19' underlying the forward end of the plate 18 and a rear cross bar 19" to which we attach the lower ends of a pair of rack bars later described. Vertically disposed angle bars 20 and 20' are 70 secured to the vertical rear edges of the extensions and have their ends fastened also to the bars 17 and 17' and the bars 19. Angularly disposed brace bars 21 are also secured to the inner faces of the extensions and to 75 the bars 17 and 17' and those 20 and 20' and the bars 21 support a cross bar 22 to which we pivotally connect a main centrally located brace bar 22' which has its rear end slotted as indicated at 22" and receiving slidably a 80 cross pin 23 carried by the forked lower end of the bearing 23' permanently secured to the under side of the platform. In the lowermost position of the main plow, the pin is engaging the forward end of the slot so that the bar 22' materially reinforces the forward end of the plow when the same is working, taking the major part of the thrust and directing it back to the platform.

The plate 18 is provided centrally of its 85 length with two normally closed hinged gates 24 and 24' which can be opened as occasion demands, the gates in their open position resting against the side boards 16.

Directly underneath the gates, we locate an 90 endless driven conveyor indicated generally by the reference numeral 25 and embodying opposing side boards 26, a cross plate 27 connecting the same, upper and lower cross shafts 28 and 28' carried by the side boards, pairs of 100 chain wheels 29 on the shafts, opposing endless chains 29' carried by the chain wheels and cross slats 30 carried by the chains, the arrangement being such that when the shafts are driven, the ascending sides of the chains 105 drag the cross bars over the upper face of the plate 27 so that the said cross bars will elevate any material permitted to drop thereon upon the gates being opened. The upper cross shaft 28 extends also through the side 110 boards 16.

The side boards 26 have their upper ends mounted on the shaft 28 and their lower ends are suspended from the angle bars 17 and 17' by suitably positioned yoke-bars 31 and 31' 115 bent to span the conveyor and fastened to the sides of the conveyor and having their extending ends permanently fastened to the angle bars 17 and 17' (see Figure 6). To the cross bar 19", we permanently fasten the lower end of a pair of spaced vertically disposed rack bars 32 and 32'. The rack bars have their upper ends permanently fastened to the outer faces of the side boards 26 of the conveyor and such rack bars are slidably received in pairs of bearings 33 located at and carried by the forward end of the platform. A cross shaft 34 is rotatably mounted in suitable bearings carried by the platform and this shaft is provided with pinions 34' mesh- 120 125 130

ing continuously with the teeth of the rack bars.

One end of the shaft 34 is provided with a worm gear 35 which is continuously in mesh with a worm 36 located at the lower end of a vertically extending adjusting shaft 36, the upper end of which is provided with a hand wheel 36.

The side boards 16 of the plow support 10 an upper somewhat U-shaped operator's platform 37 and the platform carries a bearing 37' slidably receiving the shaft 36, this permitting of the platform rising with the plow when the shaft 36 is adjusted to vary the 15 position of the nose or front end of the plow in relation to the ground. Obviously a turning movement of the shaft 36 will rotate the cross shaft 34 and effect through the pinions and racks the raising or lowering 20 of the plow and the worm and worm wheel insure of the plow remaining in any adjusted position. A motor 38 is mounted on the rear end of the platform 37 and drives the upper shaft 28 in any suitable manner such as 25 through a worm 38' and worm wheel 38.

The platform 1 is provided centrally in a location underlying the discharging end of the plow with a vertical king bolt 39 centering a turn table 40 and the turn table carries upwardly extending similar side bars 41 and 41' which span the lower end of an endless conveyor 42 constructed in the same general manner as the conveyor 25, the lower cross shaft 42' of the conveyor 42 being rotatably mounted in the upstanding bars 41 and 41' and the upper cross shaft 42" of the latter conveyor being driven by a motor 43 suitably mounted on one of the side frames or boards of such latter conveyor, the driving connection being a worm 43' operated by the motor and a worm wheel 43" secured to the shaft 42". The side bars 41 and 41' support a hopper 44 positioned underneath the upper end of the plow 15 and adapted to collect and direct the material discharging from the plow onto the lower end of the conveyor 42.

The upper ends of the bars 41 and 41' are provided with opposing bearings 45 which support a cross shaft 46 and the rear end 50 of the conveyor 42 carries a spanner bar 47. A double block and pulley tackle indicated generally by the reference numeral 48 extends between the bar 47 and the shaft 46, one end of the pulling line being anchored to the shaft 46 and the other end being passed downwardly to a winding drum 49 carried by a cross shaft 49' having the ends thereof rotatably mounted in the upright arms 41 and 41'. The shaft 49' is actuated by a winding crank 49" and a gear wheel 51 and engaging dog 51' lock the drum against rotation in one direction. According to the above arrangement, one can raise or lower the rear end of the conveyor 42 by manipulating the 65 crank.

As above described, the forward end of the conveyor 42 is mounted on the platform so that the rear end thereof can be swung laterally to discharge its load where desired either centrally of the track or at the sides thereof and suitable means is provided for laterally swinging the conveyor, such being herein shown as a worm wheel 52 associated with the turn table, a worm 52' engaging the worm wheel and carried by a shaft 53, the shaft being provided with a bevel gear 53' which meshes continuously with a further bevel gear 54' located at the lower end of a vertically disposed operating shaft 54 which extends upwardly slidably through the platform 37 and is provided with a hand wheel 54". According to this arrangement, the operator can by manipulating the hand wheel 54" position the rear end of the conveyor 42 to wherever he desires to dump the load and the conveyor becomes automatically locked in any adjusted position through the worm and worm wheel drive provided.

The nose or front end of the plow 15 is of such a width that it will clear snow or other material from the track but is not wide enough such that it will interfere with any of the various switching or signalling devices customarily used on railroads and appearing at the sides of the track. It is desirable in some locations to clear away snow or other material lying to the outer sides of the tracks and for this purpose we have provided side plows in the form of conveyors both similarly constructed and both arranged so that they can be vertically adjusted in respect to the ground and without altering the angular position of the conveyors and so that they can have their front ends raised or lowered to allow the plow to pass over an obstruction at the side of the track when the same is encountered. The side plows or conveyors can also be used to advantage for handling snow or other material appearing in the area between a main line track and a switch line track, the right or left side conveyor being chosen depending on whether the switch track is to the left or right hand side of the main track. As the structural details of the two side plows are identical as is also the manner in which they are adjusted a description of one will suffice.

On the side of the platform, we mount pairs of bearings 55 and 55' which support rotatably a lengthwise extending shaft 56 and the shaft is fitted between the bearings of the pairs with pinions 56'. The platform is provided also with bearings 57 which slidably receive the lower ends of similar vertically disposed rack bars 58 and 58', the rack bars being continuously engaged by the pinions 56'. The upper portions of the rack bars are slidably received in upper bearings 59 permanently attached to a brace bar 60 ex-

tending lengthwise of the platform and fastened thereto at intervals.

The forward end of the shaft 56 is fitted with a worm wheel 56^x which meshes continuously with a worm 61 located at the lower end of a vertically disposed adjusting shaft 62, this shaft extending upwardly slidably through the platform 37 and being provided at its upper end with a hand wheel 62'. The 10 rack bars support the side plow or conveyor which is indicated generally by the reference numeral 63. The side conveyor is structurally of the same form as the conveyor 42 so that it is not considered necessary to describe 15 in detail the various parts thereof.

The lower end of the side conveyor is provided with an inclined scoop 64 suitably fastened to the side boards 65 of such conveyor and is adapted to pick up material from the ground and deliver the same onto the lower end of the conveyor. The upper end of the conveyor 63 is pivotally supported by the upper conveyor cross shaft 66 which has the ends thereof rotatably carried in inner and outer bearings 66' and 66^x provided. The upper ends of the rack bars 58 and 58' are connected by a side bar 67 and the side bar carries an upstanding standard 68 which supports the bearing 66' and a further angularly disposed standard 69 which passes outwardly underneath the upper end of the conveyor 63 and supports the bearing 66^x. A brace bar 70 extends between the upper end of the standard 69 and the upper end of the rack bar 58'. A further brace bar 71 connects the upper end of the rack bar 58' with the lower end of the rack bar 58 and to the lower end of the bar 71, we permanently fasten an angularly disposed bracket 71' which has the upper end thereof out turned and underlying the inner side beam 65 of the conveyor 63, the said bracket supporting the lower end of the side conveyor in its lowermost position.

The side boards 65 carry at their lower ends a cross shaft 72 on which we slidably mount a sleeve 72' (see Figure 4) and to the sleeve, we connect pivotally the forked end of a tube 73 which receives telescopically the forward end of a rod 73', the rear end of which is connected by a ball and socket joint 74 to the rack bar 58'. The tube is longitudinally slotted at the sides as indicated at 75 and the slots receive the extending ends of a cross pin 75' passing through the forward end of the rod and when the conveyor 63 is in its lowermost position, the pin is engaged with the forward ends of the slots and the sleeve is at the outer end of the rod 72 and accordingly, the outer side of the nose or lower end of the conveyor 63 is supported by the tube and rod and the latter also act to take considerable of the thrust brought on the lower end of the conveyor scoop when it is working.

65 The upper end of the side conveyor in each

instance is adapted to discharge the material elevated thereby into an inclined cross chute 76, the outer end of which is supported in each instance by the bar 70 and the inner end of which discharges over the upstanding sides of a collecting pan 77 carried centrally by the platform 1 and having an inclined bottom directing the material discharged there onto towards the lower end of the conveyor 42. The inner end of the chute is supported by a brace 78 having the lower end fastened to the bar 67 and the upper end secured to the under side of the chute, it being here remembered that the chute moves up and down with the conveyor 63 when the rack bars are adjusted. The vertical adjustment permitted the side conveyor allows us to vary the position of the scoop 64 in respect to the ground and without altering the inclined position of the said conveyor.

As the side conveyors extend considerably to the sides of the track rails, they will strike the various switching and signalling devices adjacent the track unless provision is made for lifting the forward end of the side conveyors to pass over the obstruction. Obviously various types of lifting appliances may be used for this purpose. We have shown a special rack and pinion elevating device which is shortly described.

On the inner side of each of the side conveyors or plows, we have mounted a motor 79 and the motor shaft 79' is provided with a worm 80 meshing continuously with a worm wheel 80' secured to the inner end of the driving shaft 66 of the side conveyor. This motor is of the reversible drive type and when driven in one direction, operates the side conveyor so that it will elevate the material discharged thereon by the scoop. We have provided, however, clutch members indicated generally by the reference numeral 81 associated with the motor shaft and adapted to remain in engagement and effect the driving of the conveyor 63 for elevating purposes upon the motor shaft being turned in one direction and to slip past so that the conveyor will not be driven when the motor shaft is rotated in the other direction.

The motor shaft is also extended and utilized as a drive for a worm 82, the worm being continuously in mesh with a worm wheel 83 rotatably mounted on the inner side board 65 of the conveyor 63 and driving a smaller pinion 84 held continuously in mesh with the teeth of a rack bar 84'. The lower end of the rack bar is pivotally connected at 85 to the rack bar 58 and the arrangement is such that when the worm 82 is driven, the pinion 84 will ride the rack bar 84' and consequently raise or lower the forward end of the conveyor 63 as occasion demands.

The motor shaft extended to drive the worm is a split shaft and carries a clutch member 85 fastened to one of the split ends

of the shaft which clutch member rotatably supports the other of the split ends of the shaft. A further clutch member 86 is feathered on the latter split end of the shaft and is adapted to be engaged with the other clutch member when desired by the attendant. A pulling lever 87 extends upwardly through the platform and has the lower end slidably carried in a suitable bearing adjacent the motor 79 (see Figure 5) and the lower end of the lever is connected by a link 88 pivotally to the clutch member 86, the arrangement being such that the end shifting of the lever 87 engages or disengages the clutch members 85 and 86. The upper end of the lever 87 passes slidably through the platform 37 and the lever carries a dog 89 and a hand latch 90, the dog locking the lever in the position where the clutch members 85 and 86 are disengaged.

By providing the split shaft between the motor and the worm 82 and utilizing the clutch members 85 and 86 together with the clutch members 81, we avoid the reverse driving of the conveyor 63 when the forward or nose end of the said conveyor is being lowered subsequent to the same having been raised to pass an obstruction such as a switch stand. When the nose of the side conveyor 39 is being raised to avoid an obstruction, the conveyor is being driven by the motor 79 in a direction such that the upper sides of the conveyor chains thereof are ascending but when the nose of the side conveyor is being lowered by the rack and pinion action, the clutch members 81 are slipping past one another so that the conveyor chains are not driven.

Under certain circumstances, it may be advantageous to dispense with the side conveyors and the chutes 76 and substitute elevating chutes and in Figure 10, we have shown the type of chute which can be used.

When the chute indicated generally by the reference numeral 91 is to be used, the side conveyors are removed, this being accomplished by disconnecting the various side conveyor supporting bars attached to the rack bars 58 and 58'. We then bolt the blocks 92 and 92' (see Figure 10) to the rack bars 58 and 58' and these blocks carry pivotally outstanding arms 93 and 93' which are free to swing upwardly but are stopped in their horizontal position by contact of the inner ends thereof with the blocks as best shown in Figure 11. The arms carry the main plate 94 of the chute which is provided at the outer side with an upstanding fixed guard wall 95 and at the inner side with a hinged upstanding wall 95' which when desired can be swung down against the plate 94. The upper end of the wall 95 is turned inwardly across the plate 94 and a side chute 96 is hinged to the inner side of the plate, this chute being adapted to discharge the mate-

rial pushed up by the elevating chute onto the pan 77 in the same manner as was done by the chute 76.

When an obstruction is met, the elevating chute as shown in Figure 10 is swung upwardly so that the outer edge thereof will clear the same and the chute 96 will accommodate itself by virtue of its hinged connection to whatever movement is given the side chute.

What we claim as our invention is:

1. In combination, a portable platform, a forwardly extending inclined plow overlying the forward end of the platform, a rigid frame work underlying the forward end of the plow and embodying vertically disposed rack bars adjacent the forward end of the platform, bearings carried by the platform and slidably receiving the rack bars, a cross shaft carried by the platform, pinions mounted on the shaft and engaging the rack bars and means operable from a distant point for rotating the shaft to raise or lower the plow.

2. In combination, a portable platform, a forwardly extending inclined plow overlying the forward end of the platform, a rigid frame work underlying the forward end of the plow and embodying vertically disposed rack bars adjacent the forward end of the platform, bearings carried by the platform and slidably receiving the rack bars, a cross shaft carried by the platform, pinions mounted on the shaft and engaging the rack bars, means operable from a distant point for rotating the shaft to raise or lower the plow, a brace bar centrally underlying the plow and having the forward end thereof pivotally attached forwardly to the frame work and the rear end thereof anchored to the platform, said latter connection being designed such that the brace bar reinforces the forward end of the plow in its lowermost position and permits of a sliding movement of the brace bar upon the plow being vertically adjusted.

3. In combination, a portable platform and a forwardly disposed inclined plow carried thereby, said plow embodying an elevating plate and an endless driven conveyor underlying the same, said plate having a portion thereof which can be opened to expose the conveyor.

4. In combination, a portable platform, an inclined main plow carried by the forward end of the platform and provided with an elevating plate over which the material dug by the plow is delivered, an endless driven conveyor carried by the plow and underlying the plate and gates associated with the plate and adapted when opened to expose the conveyor.

5. In combination, a portable platform, a main inclined plow carried by and overlying the forward end of the platform, said

plow embodying an elevating plate over which the material dug by the plow is delivered, an endless driven conveyor underlying the plate and embodying a cross plate over which the ascending side of the conveyor drags and gates formed in the plate of the plow and adapted when opened to expose the conveyor.

6. In combination, a portable platform, a vertically adjustable inclined main plow carried by the forward end of the platform and delivering rearwardly, similar rearwardly delivering inclined side plows carried by the sides of the platform and bodily vertically adjustable in respect thereto and having their rear ends pivotally mounted and their forward ends vertically adjustable, a rear inclined and driven conveyor carried by the platform, said conveyor being mounted to permit of the lateral swinging movement of the conveyor and of the vertical adjustment of the rear end thereof and having the forward end thereof underlying the rear end of the main plow, a collecting pan carried by the platform adjoining the lower end of the rear conveyor and cross chutes receiving from the rear ends of the side plows and delivering to the pan.

7. The combination with a portable platform and an inclined rearwardly delivering main plow carried by the forward end of the platform, of similar inclined rearwardly delivering side plows located at the sides of the platform, vertically disposed rack bars slidably carried by the platform and supporting the side plows, shafts rotatably carried by the platform, pinions secured to the shafts and engaging the rack bars and means for rotating the shafts to actuate the rack bars.

8. The combination with a portable platform and an inclined rearwardly delivering main plow carried by the forward end of the platform, of inclined rearwardly delivering side plows located at the sides of the platform and carried thereby and bodily vertically adjustable in respect thereto and each independently swung to permit of the raising or lowering of the forward end thereof.

9. The combination with a portable platform and an inclined rearwardly delivering main plow carried by the forward end of the platform, of similar rearwardly delivering inclined side plows carried by the sides of the frame and mounted to permit of vertical adjustment without altering the angular position thereof and of the raising of their forward ends to pass road obstructions.

10. The combination with a portable platform and an inclined rearwardly delivering main plow carried by the forward end of the platform, of similar plow supporting frame structures located at the sides of the platform and embodying vertically disposed rack bars adjacent the platform, bearings carried by the platform and slidably receiving the

rack bars, shafts rotatably carried by the platform, pinions secured to the shafts and engaging the rack bars, means for rotating the shafts to adjust the rack bars and elevate or lower the frames and similar rearwardly delivering plows carried by the frames and vertically adjustable therewith and having their rear ends pivotally mounted and their front ends vertically adjustable.

11. In combination, a portable platform a rearwardly delivering inclined main plow carried by the forward end of the platform and vertically adjustable in respect thereto said plow embodying an elevating plate, an endless conveyor underlying the same and gates associated with the plate and adapted when opened to expose the conveyor, an elevated operator's platform carried by the plow and vertically adjustable therewith and motor mounted on the platform and driving the adjacent upper end of the conveyor.

Signed at Winnipeg, this 2nd day of August, 1929.

JOHN W. McCALLUM.
ALEC S. MUSCOVITCH.
